FRANK RICHARD PETERS, OF NEW YORK, N. Y., ASSIGNOR TO FRANKLIN RAILWAY SUPPLY COMPANY, OF NEW YORK, N. Y., A CORPORATION OF DELAWARE

SELECTIVE CONTROLLING MEANS FOR A PLURALITY OF LOCOMOTIVE BOOSTER MOTORS

Application filed September 27, 1930. Serial No. 484,853.

This invention relates to locomotive booster motors and particularly to an improved means for selectively controlling any one or more of said boosters where a plurality of them has been employed.

Many of the modern locomotives are now being equipped with what has become known in the art as the locomotive booster. This is a device for aiding the locomotive either in starting or at slow speeds where the pulling is heavy. The boosters are arranged to drive axles either on the locomotive proper or the tender, and since the wheels of such axles are generally of a diameter which is considerably smaller than the diameter of the main drivers of the locomotive, it is customary to provide suitable mechanism for entraining the booster only at times when it is to become operative as a driving factor so that it may be disengaged when not in use.

Furthermore, controlling mechanism has been provided for the boosters which is arranged so as to be subordinated to the controlling mechanism for the main locomotive in order to impose no additional burden upon the engineer in running his train.

As the use of booster motors has become more and more prevalent, it has become increasingly desirable to employ more than one booster for each locomotive, especially where the traffic is sufficiently heavy to warrant the expense. It has also become customary to provide means whereby the boosters can be thrown into operation during either forward or reverse motion of the locomotive.

With the foregoing in mind, the primary object of my invention will be more clearly appreciated and understood and it can be said that this object contemplates the provision of a selective controlling means for a plurality of boosters by means of which any one or any combination of the boosters may be put into operation without in any way interfering with the automatic character of the customary booster controlling devices and regardless of whether or not the locomotive is running forwardly or backwardly.

Specifically considered, it is the object of my invention to provide what I have termed a selective valve which I place in the air sup-

ply lines provided for controlling the boosters, which valve is so constructed as to make possible, by means of the actuation of a single lever, the operation in either a forward or a backward direction of any one or all of the boosters on a locomotive.

The foregoing, together with such other objects as may appear hereinafter, or are incident to my invention, are obtained by means of a construction which is illustrated in the preferred form in the accompanying drawings, wherein—

Fig. 1 is a diagrammatic showing of a double booster installation in which I have incorporated my improved selective control mechanism.

Fig. 2 is a vertical longitudinal section through my improved selective valve.

Fig. 3 is a front elevation of my improved selective valve.

Fig. 4 is a plan view of the said valve, and

Fig. 5 is a section on the line 5—5 of Fig. 2.

Fig. 1 includes a diagrammatic showing of well known booster controlling mechanism, the details of which per se form no part of the present invention and which, therefore, will not be more fully illustrated, but in connection with which, if so desired, reference may be had to the Forker Patent No. 1,778,757, issued on October 21, 1930, the Roberts Patent No. 1,789,691, issued January 20, 1931, the Roberts and Forker Patent No. 1,686,710, issued October 29, 1928, and my own prior Patent No. 1,736,886, issued November 26, 1929.

In the diagram two boosters 6 and 7 are illustrated and they are adapted to be connected to drive the axles 8 and 9 through the gearing indicated as a whole by the characters 10 and 11 respectively.

Steam is supplied to the boosters through the steam pipes 12 and 13 which are connected to the locomotive steam chest and in which are located the booster throttle valve mechanisms 14 and 15.

In addition the controlling mechanism for each booster includes the usual preliminary throttle valve 16, the customary cylinder 100

cock mechanism 17, dome pilot valve 18 and timing reservoir 19.

From the foregoing it will be seen that each booster is provided with a complete controlling system and these systems are preferably fluid actuated in accordance with customary practice, the fluid being taken preferably from the air reservoir and entering the controlling systems through the pipe 10 20.

The pipe 20 delivers the air to the reverse lever pilot valve 21 which is also well known in the art and which is directly associated with the reverse lever 22. The details of 15 this reverse lever pilot valve are disclosed and claimed in the Forker Patent No. 1,778,757, above referred to, but in the said patent one booster only is shown.

The description so far relates to devices 20 which are well known in the art. My invention involves the use of the selective valve 23, the details of which are illustrated in Figs. 2 to 5 inclusive and which can be constructed in accordance with the present invention, as will hereinafter appear, so as 25 to make possible the operation of any one or any combination of boosters on the locomotive.

To complete the brief description of the 30 diagram of Fig. 1 it should be noted that upon manipulation of the lever 24 the engineer can deliver air pressure to the line 25 which is connected to the port 25a on the top of my improved selective valve. When the 35 reverse lever 22 is in the forward corner or in its right hand position air pressure is delivered to the pipe 26 which is connected to the port 26a at the top of my selective valve, and when the reverse lever 22 is moved to 40 the rear corner or to its left hand position air pressure is delivered to the pipe 27 which is connected to the port 27a on the top of my selective valve.

The air coming through the pipe 25 and 45 the port 25a is for the purpose of operating the preliminary throttle valves 16, and upon proper manipulation of the lever 28 this air can be delivered to either or both of the preliminary throttle valves 16 through the pipes 50 25b and 25c which are connected, respectively, to the ports 25d and 25e at each side of my selective valve.

The air coming through the pipe 26 can 55 be delivered to either one or both of the boosters through the pipes 26b and 26c connected to the ports 26d and 26e at the sides of my selective valve. The air coming through the pipe 27 can be delivered to either one or both of the boosters through the pipes 60 27b and 27c which are connected, respectively, to the ports 27d and 27e at the sides of my selective valve.

Air passing through pipes 26 and either or 65 both of said pipes 26b and 26c will actuate the boosters for forward motion of the loco-

motive and the air coming through pipe 27 and passing through either or both of the pipes 27b and 27c will actuate the booster for reverse motion of the locomotive.

My improved selective valve includes the 70 shell or housing 29 provided with a suitably apertured flange 30 by means of which it can be secured in any desired location.

Within the housing 29 is a tapered rotary plug valve 31 provided in its upper part with 75 three slots 25f, 27f and 26f.

In the lower portion of the housing is formed an exhaust passage 32 which is open to the atmosphere through the port 33.

The small end 34 of the plug valve projects beyond the front wall of the housing and carries the operating handle 28 already referred to. Within the hub 35 of the handle 28 is a spring pressed ball or latch 36 adapted to hold the valve in any selected position of 80 adjustment which, in the present instance, would be for any one of the positions shown in Fig. 3, viz., for both boosters, which is the central position, for the front booster, which is the right hand position, or for the rear booster, which is the left hand position, as indicated in Fig. 3.

The plug valve 31 is inserted through an opening in the rear of the housing 29 and is held in place by means of the spring 37 and the threaded cap 38. Under normal or forward operating conditions, in order to ensure a perfectly tight valve regardless of the wear which may take place, I provide a connection 39 between the dust or channel 26f and the rear face 40 of the valve so that whenever the boosters are in operation and the valve is performing its function, there will always be pressure on its rear face tending to urge it 90 forwardly against the taper and thereby 100 maintaining a perfectly tight fit.

It will now be apparent that if the engineer wishes to utilize both of the boosters, he simply moves the lever 28 to the position marked "Both" whereupon the air which will be delivered to the selective valve from the reverse lever pilot valve through the several pipes 25, 26 and 27 will be free to pass outwardly at the sides of the selective valve through the ports 25d, 25e, 27d, 27e, 26d and 26e as already described.

If only the front booster (that is, the booster farthest forward on the locomotive) is desired, the lever 28 is turned to the front position and air coming from the reverse lever pilot valve can pass outwardly only through the ports 25d, 27d and 26d, and at the same time any air which may be trapped in the controlling system for the rear booster is free to exhaust through the port 33 by virtue of the slots 25g, 27g and 26g in the lower portion of the plug valve which, as will be seen upon inspection of Figs. 2 and 5, are arranged to connect the ports 25e, 27e and 26e 125 130 135

to the exhaust passage 32 and the exhaust port 33.

If desired, the hub of the operating lever 28 may be provided with some suitable indicating device, such as the arrow 41.

I wish it to be distinctly understood that while I have illustrated two boosters in connection with my improved selective valve, it is quite obvious that more than two boosters might be controlled by a device of the same character, it being necessary to increase the number of connections as the number of boosters increases.

What I claim is:—

1. The combination of a plurality of boosters, a controlling mechanism for each booster, and a common controlling unit for said mechanisms including means for effecting operation of any one or of any combination of said boosters.

2. The combination of a plurality of boosters, fluid actuated controlling means for each booster, a source of fluid supply, and a valve for controlling said fluid supply adapted to be moved to positions where any one or any combination of said boosters may be put into operation.

3. A valve for controlling the supply of fluid to a plurality of fluid actuated booster controlling mechanisms, said valve including a preliminary throttle connection, a forward motion connection and a reverse motion connection for each controlling mechanism, and a movable member adapted to establish said connections for any one or any combination of said controlling mechanisms.

4. A valve for controlling the supply of fluid to a plurality of fluid actuated booster controlling mechanisms, said valve including a preliminary throttle connection and a booster actuating connection for each controlling mechanism, and a movable member adapted to establish said connections for any one or any combination of said controlling mechanisms.

5. The combination of a plurality of boosters, fluid actuated controlling means for each booster, a source of fluid supply, and a valve for controlling the supply, said valve having a connection to each booster controlling means and an exhaust opening and being adapted to be moved so as to deliver fluid to any one or any combination of said booster controlling means and also to connect the controlling means for an idle booster to said exhaust when other booster controlling means are receiving fluid.

6. A valve for controlling the supply of fluid to a plurality of fluid actuated booster controlling mechanisms, said valve including a preliminary throttle connection and a booster actuating connection for each controlling mechanism as well as an exhaust opening, and a movable member adapted to establish said connections for any one or any

combination of said controlling mechanisms and also to connect the controlling mechanism for an idle booster to said exhaust when other booster controlling mechanisms are receiving fluid.

7. A valve for controlling the supply of fluid to a plurality of fluid actuated booster controlling mechanisms, said valve including a preliminary throttle connection, a forward motion connection and a reverse motion connection for each controlling mechanism as well as an exhaust opening, and a movable member adapted to establish said connections for any one or any combination of said controlling mechanisms and also to connect the controlling mechanism for an idle booster to said exhaust when other booster controlling mechanisms are receiving fluid.

In testimony whereof I have hereunto signed my name.

FRANK R. PETERS.
